SPENT BOBBIN RECEIVER FOR LOOMS

Walter H. Wakefield, Worcester, Mass., assignor to Crompton & Knowles Loom Works, Worcester, Mass., a corporation of Massachusetts

Application December 22, 1945, Serial No. 636,953

18 Claims. (Cl. 139—255)

1

This invention relates to improvements in spent bobbin receivers for weft replenishing looms and it is the general object of the invention to provide a receiver which can be easily manipulated for the purpose of emptying the bobbins accumulated in it.

Weft replenishing looms of the bobbin changing type ordinarily have provision for discharging the spent bobbins downwardly from the shuttle into a can or the like. In the past these cans have been made of sheet metal and have been heavy and difficult to empty. It is an important object of my present invention to provide a pivotal mounting for a bobbin receiver so constructed that it can be swung forwardly to a position in which the bobbin receiving mouth of the receiver will be either inverted or be in an advantageous position to facilitate emptying of the bobbins.

Ordinarily the bobbin receiver must be held in its normal bobbin receiving position with its mouth facing upwardly and it is a further object of my invention to provide a detachable connection between the receiver and a support therefor normally operative to hold the receiver in bobbin receiving position but releasable by a lateral shift of the receiver so that the latter can be rotated on the support to bobbin discharging position.

It is desirable to hold the receiver in bobbin discharging position by some means which will enable the attendant to manipulate the bobbins during the discharging operation without being required to hold the receiver. It is accordingly a still further object of my invention to provide the pivotal mounting for the receiver with a secondary holding means by which the receiver can be held with its mouth in position to simplify bobbin removal. The receiver is preferably a cloth bag suspended from a metal frame or holder, but the invention is not limited to such a receiver.

With these and other objects in view which will appear as the description proceeds, my invention resides in the combination and arrangement of parts hereinafter described and set forth.

In the accompanying drawing, wherein a convenient embodiment of my invention is set forth,

Fig. 1 is a side elevation of the forward part of a loom, partly in section, showing my improved bobbin receiver in normal position.

Fig. 2 is a detailed plan view looking in the direction of arrow 2, Fig. 1.

Fig. 3 is an enlarged front elevation looking in the direction of arrow 3, Fig. 1, indicating the manner in which the receiver can be moved laterally with respect to its support.

2

Fig. 4 is a perspective view of a part of the receiver and its support in normal position.

Fig. 5 is a detailed vertical section on line 5—5, of Fig. 3.

Figs. 6 to 9 are diagrammatic views illustrating the manner in which my invention is operated when the loom is running, and

Fig. 10 indicates the direction in which the mouth of the receiver can be turned when the loom is at rest at back center.

Referring more particularly to Fig. 1, I have shown a loom frame 10 having a lay 11 which is reciprocated backwardly and forwardly by the usual connectors one of which is indicated at 12.

15 The lay has a shuttle box 13 to receive a shuttle S from which bobbins are discharged downwardly during weft replenishing operations. The descending bobbins pass through a slot 14 in the lay and are then guided in a downwardly and 20 forwardly inclined direction by a bobbin chute 15 secured to the lay under the shuttle box. During loom operation the bobbin chute 15 traverses an arcuate path as the lay reciprocates and bobbin transfer or replenishment ordinarily occurs when 25 the lay is near its front center position.

The matter thus far described is usual in bobbin changing weft replenishing looms and of itself forms no part of my present invention.

The expelled or spent bobbins which descend 30 along the chute are collected in a bobbin receiver designated generally at R. This receiver has a top frame 20 defining a bobbin receiving mouth M and having front and back bars 21 and 22, respectively, and right and left rearwardly and 35 downwardly inclined side bars 23 and 24, respectively. As indicated in Fig. 1 the rear bar 22 is at a lower level than is the front bar 21, and is behind the forward limit of the path traversed by the chute.

40 The bobbin holding part of the receiver is preferably a cloth bag designated at 25 the upper edges of which are formed as indicated in Fig. 5 to fit around the frame 20. The bag hangs by its own weight more or less in the form shown in 45 Fig. 1, and the discharged bobbins B collect in the bottom of the bag and require emptying from time to time.

In order that the receiver may be manipulated during the bobbin emptying operation I provide 50 the loom frame 10 with a support 30 secured to the frame as at 31 and having a hub or bearing 32 through which the left end of the front bar 21 passes. Bar 21 has its left end bent upwardly to provide an arm 33 which cooperates with 55 primary and secondary stops 34 and 35, respec-

tively. These stops are fixed with respect to the support 30 and may if desired have threaded ends 36 tapped into the support as indicated in Fig. 3. The stop 34 at the upper part of the support 30 has a forwardly facing notch 40 into which the arm 33 can fit, and a similar notch 41 is provided in the bottom stop 35 to receive arm 33. The bar 21 of the frame 20 is capable of sliding and turning movements in the bearing 32, hence the support 30 provides a sliding and pivotal mounting for the receiver.

Under normal conditions arm 33 is in notch 40 and the receiver R will be held in normal position due to the fact that its weight is behind the axis of bearing 32 and arm 33 extends upwardly and is held in notch 40 against the primary stop 34. When it is desired to empty the receiver the attendant will lift the rear end of the frame 20 slightly to disengage arm 33 from notch 40, after which he will move the receiver laterally to the left a sufficient distance to move the arm 33 beyond or to the left of the stops 34 and 35, thereby disengaging the receiver from stop 34. The attendant will then rotate frame 20 in a clockwise direction in the direction of arrow a, Fig. 6, the rear bar 22 moving downwardly away from the path of chute 15. When the loom is running it is necessary to swing the frame 20 in the direction indicated in Fig. 6 due to the fact that the rear part of the bobbin receiving mouth M extends behind the path traversed by the bobbin chute and it would not be safe to swing frame 20 upwardly.

Due to the fact that the bobbin holding part of the receiver is a flexible bag the latter will take the position indicated in Fig. 6, and as the attendant continues to turn frame 20 in a clockwise movement as indicated by arrow b, Fig. 7, the back bar 22 will engage the front wall 45. Continued movement of the frame 20 will eventually bring it to the position shown in Fig. 8 with the bag depending from back bar 22 which now is in front of the bar 21 and extends into the aisle in front of the loom. The mouth of the receiver is now inverted and faces downwardly.

The arm 33 is now in the dotted line position indicated in Fig. 3, and by a slight sliding movement of the receiver to the right said arm will move in front of the secondary stop 35 and then into notch 41. The frame 20 is now supported in the inverted position shown in Fig. 8 and the attendant can lift the bag by means of a tab 42 secured to it to empty the bobbins into a carriage C or the like which is portable and is moved from loom to loom. This carriage is in the aisle in front of the loom and the inverted mouth of the receiver will be over the carriage when the parts are in the position shown in Fig. 9.

The bag 25 is then allowed to return to the position shown in Fig. 8, after which the operations described are reversed, that is, arm 33 is detached from notch 41 and the frame 20 slid laterally to the left as viewed in Fig. 3 so that arm 33 can swing upwardly clear of both the secondary and primary stops, after which a slight lateral movement to the right will reestablish the receiver in its normal position with the arm 33 in notch 40.

The operation just described applies when the loom is running, but if it is at rest with chute 15 in rearward position, it is obvious that frame 20 can be turned in a counter-clockwise direction without sliding bar 21 in bearing 32, see arrow c, Fig. 10. When operated in this

manner the bag will be as shown in Fig. 10 prior to lifting to the position of Fig. 9.

From the foregoing it will be seen that I have provided a simple mounting for a spent bobbin receiver of a weft replenishing loom, the receiver being rotatable about an axis which as shown herein is horizontal and substantially parallel to the length of the lay as seen in Fig. 2 so that the mouth of the receiver can be swung to a forward inverted position to facilitate emptying of the bobbins. It will also be seen that the mounting 30 provides a sliding and pivotal support for the receiver, and that slight lateral movements of the receiver affect disengagement of it with respect to the holding or supporting stops 34 and 35, thereby enabling the frame 20 to be turned as described. During loom operation the chute traverses a path the forward part of which extends over the rear part of the receiver mouth M, and under these conditions the frame 20 should be turned in the direction indicated by arrows a and b in Figs. 6 and 7, respectively. When the loom is at rest, however, and the chute is in rearward non-interfering position the frame 20 can be turned in a counter-clockwise direction indicated in Fig. 10 without sliding the receiver laterally relatively to mounting 30.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom having a lay and bobbin chute thereon which moves along a given path as the lay reciprocates, a spent bobbin receiver having a mouth through which bobbins pass from the chute to the receiver, and mounting means for the receiver including a pivotal support for the mouth having an axis parallel to the lay to enable said mouth to be moved downwardly from said path and then forwardly to an inverted position to facilitate emptying of the receiver.

2. In a weft replenishing loom having a lay and bobbin chute thereon which moves along a given path as the lay reciprocates, a spent bobbin receiver having a mouth through which bobbins pass from the chute to the receiver, and means constituting a substantially horizontal pivotal support for the mouth having an axis substantially parallel to the lay and so constructed that said mouth can be swung downwardly from said path and forwardly relatively to the lay to an inverted position to facilitate emptying of the receiver.

3. In a weft replenishing loom having a lay and bobbin chute thereon which moves along a given path as the lay reciprocates, a spent bobbin receiver including a flexible bag and having a mouth extending under said path and through which bobbins pass from the chute to the bag, and means supported by the loom providing a pivotal mounting for the receiver, the axis of said mounting being substantially horizontal and parallel to the lay, and the mouth being rotatable about said axis in a direction downwardly from said path and then forwardly to an inverted position to facilitate emptying of the bag.

4. In a weft replenishing loom having a lay and bobbin chute thereon, a spent bobbin receiver having a bobbin receiving mouth, a pivotal support for the receiver having an axis substantially parallel to the lay, said receiver being slidable on said support in a given direction parallel to

said axis, and means normally engaging said receiver and supporting the latter with the mouth thereof facing upwardly, said receiver when sliding relatively to said pivotal support in said given direction becoming disengaged from said means and being thereafter rotatable around said axis in a direction forwardly from said path to an inverted position to facilitate emptying of the receiver.

5. In a weft replenishing loom having a lay and bobbin chute thereon, a spent bobbin receiver having a bobbin receiving mouth, a pivotal support for the receiver having an axis substantially parallel to the lay, said receiver being slidable on said support in a given direction parallel to said axis, means normally engaging said receiver and supporting the latter with the mouth thereof facing upwardly, said receiver when sliding relatively to said pivotal support in said given direction becoming disengaged from said means and being thereafter rotatable around said axis in a direction forwardly from said path to an inverted position to facilitate emptying of the receiver, and additional means engageable with said receiver when the latter slides relatively to said pivotal support in a direction opposite to said given direction while said mouth is inverted to engage and hold the receiver with said mouth inverted.

6. In a weft replenishing loom having a lay and bobbin chute thereon which moves along a given path as the lay reciprocates, a spent bobbin receiver having a bobbin receiving mouth, a pivotal support for the receiver having an axis substantially parallel to the lay and with respect to which the receiver is slidable in a given direction parallel to said axis, primary stop means engaging said receiver and normally supporting the latter with said mouth facing upwardly and extending under said path, said receiver when moved slidably in said given direction moving out of engagement with said primary stop means and being thereafter rotatable in a direction downwardly from said path and then forwardly to a position in which the mouth is inverted, and a secondary stop means to engage said receiver when the latter is thereafter moved slidably in a direction opposite to said given direction and hold said receiver with said mouth inverted.

7. In a weft replenishing loom having a lay and bobbin chute thereon which moves along a given path as the lay reciprocates, a spent bobbin receiver including a flexible bag and having a mouth through which bobbins pass from the chute to the bag, a pivotal support for the receiver having an axis parallel to the lay and with respect to which the receiver is slidable in a given direction parallel to said axis, and stop means engaging said receiver and normally supporting the latter with said mouth facing upwardly and extending under said path, said receiver when moved slidably in said direction out of engagement with said stop means being rotatable in a downward direction away from said path and then forwardly to a position in which said mouth is inverted.

8. In a weft replenishing loom having a lay and bobbin chute thereon which moves along a given path as the lay reciprocates, a spent bobbin receiver including a flexible bag and having a mouth through which bobbins pass from the chute to the bag, a pivotal support for the receiver having an axis parallel to the lay and with respect to which the receiver is slidable in a given direction parallel to said axis, primary stop means engaging said receiver and normally supporting

the latter with said mouth facing upwardly and extending under said path, said receiver when moved slidably in said direction out of engagement with said stop means being rotatable in a direction downwardly from said path and then forwardly to a discharge position in which said mouth is inverted, and secondary stop means engageable with said receiver when the latter is in discharge position and is moved in a direction opposite to said given direction to hold said receiver with the mouth thereof inverted.

9. In a weft replenishing loom having a lay provided with a bobbin chute, a receiver for spent bobbins projected downwardly along said chute, and pivotal support means for the receiver having a horizontal axis parallel to the lay around which the receiver can be swung forwardly from said chute to an inverted position.

10. In a weft replenishing loom having a lay provided with a bobbin chute which swings backwardly and forwardly along a given path, a receiver for spent bobbins projected downwardly along said chute extending under said path, and pivotal support means for the receiver having a horizontal axis parallel to the lay around which the receiver can be swung downwardly from said path and then forwardly to an inverted position.

11. In a weft replenishing loom having a reciprocating lay provided with a bobbin chute down which exhausted bobbins travel incident to replenishing operations of the loom, said chute swinging along a given path as the lay reciprocates, a bobbin receiver having a mouth extending under said path to receive said bobbins and including a flexible bag to hold said bobbins, and means normally holding said receiver with the mouth thereof opening upwardly in position to receive said bobbins from the chute, said means including a pivotal support for the receiver having an axis so disposed that the mouth of the receiver can be swung downwardly from said path and then forwardly and upwardly to cause said mouth to face downwardly to facilitate emptying the bobbins from said bag.

12. In a weft replenishing loom from which spent bobbins are discharged during weft replenishing operations, a receiver having a normally upwardly facing mouth through which the bobbins pass into said receiver, and a pivotal support for said receiver having a horizontal axis around which the receiver can be swung to move said mouth to an inverted position.

13. In a weft replenishing loom from which spent bobbins are discharged downwardly, a receiver including a rigid frame at the upper part thereof formed to define a normally upwardly facing mouth, and a pivotal support for said frame having a substantially horizontal axis located at a level above that part of the receiver which holds the bobbins and around which said frame can be turned from the normal position thereof to a position in which the mouth faces in a direction to facilitate emptying of the bobbins from the receiver.

14. In a weft replenishing loom from which spent bobbins are discharged downwardly, a receiver including a flexible bag and a normally upwardly facing mouth through which said bobbins pass into said bag, and means mounting said mouth for movement about a horizontal axis near the forward part of the frame forwardly from the normal position thereof to a position in which the bobbins will fall through said mouth when the bottom of said bag is raised above said mouth.

15. In a weft replenishing loom from which

spent bobbins are discharged downwardly, a receiver for said bobbins including a rigid frame at the upper part thereof, a flexible bag depending from said frame, the latter defining a mouth through which said bobbins move downwardly into the bag, and means mounting said frame for movement about a horizontal axis near the forward part of the frame forwardly from the normal position thereof to a position in which said bag when raised above said frame will effect emptying of the bobbins in the bag through said mouth.

16. In a weft replenishing loom from which spent bobbins are discharged downwardly, a spent bobbin receiver including a rigid frame at the upper part thereof, a flexible bobbin bag suspended freely from said frame, the latter formed to provide a mouth through which the downwardly discharged bobbins pass into the bag, a bearing on the loom having a horizontal axis near the upper forward part of the receiver and receiving a part of the frame which is rotatable in the bearing, said frame being swingable downwardly and forwardly around said axis to a position such that when the bag is elevated to a level above said frame the bobbins in said bag will be discharged downwardly through said mouth.

17. In a weft replenishing loom having a lay from which depleted bobbins are discharged downwardly, an open frame, means on the loom mounting the forward part of the frame for piv-
